UNITED STATES PATENT OFFICE.

JOSEPH E. FELLER, OF BROOKLYN, NEW YORK.

ELECTRIC SIGNAL.

SPECIFICATION forming part of Letters Patent No. 754,208, dated March 8, 1904.

Application filed April 24, 1902. Serial No. 104,506. (No model.)

To all whom it may concern:

Be it known that I, JOSEPH E. FELLER, a citizen of the United States, and a resident of the city of New York, borough of Brooklyn, in the county of Kings and State of New York, have invented new and useful Improvements in Electric Signals, of which the following is a full, clear, and exact description.

My invention relates to electric signals suitable for general use, and more particularly to a type of instrument in which the person signaled may indicate to the person signaling if the signal is properly received.

Reference is to be had to the accompanying drawings, forming a part of this specification, in which similar characters of reference indicate corresponding parts in all the figures.

Figure 1 is a diagram showing two stations each equipped with a transmitter and receiver. Fig. 1^a is a fragmentary diagram showing my system as used with a single transmitter and a single receiver. Fig. 2 is a side elevation of one of the receivers. Fig. 3 is a front elevation of the same. Fig. 4 is a plan view of one of the transmitters. Fig. 5 is a vertical central section through the same. Figs. 6 and 7 are fragmentary detail views showing the contacts of the transmitter, and Fig. 8 is a fragmentary detail view of one of the signal-dials used upon the receiver.

A and B represent the respective transmitter and receiver used at one of the stations, while C and D represent the respective transmitter and receiver used at the other station. A source 1 of electric-current supply is connected by wires 2 3 with wires 4 5, leading to the transmitters A C, located at the respective stations. Movable arms 6 7 are connected, respectively, with the wires 4 5. These arms are free to move over the sector-shaped contacts 8 9, which are provided with distinguishing ordinals, as shown. Closed rings of wire 10 11 12 and 13 14 15 are provided upon the respective transmitters. These rings are connected with the sector-shaped contacts by means of wires 16 17 18 19 20 21, as indicated more clearly in Fig. 1. These rings are also connected, by means of wires 22 23 24 25 26 27, with the circuit-wires 28 29 30. The wires 2 3 are connected, by means of wires 31

32, with the respective motor-fields 33 34 of the receivers. These fields are connected with the brushes 35 36 and through these brushes with the collector-rings F G, which latter are connected by wires 37 and 38 with the receivers B and D. The wires 2 3 form a triple connection with the coils 39 40 41 of the receiver B and the coils 42 43 44 of the receiver D. The circuit-wires 28 29 30 are connected with the brushes 45 46 47 of the receiver B and 60 with the brushes 48 49 50 of the receiver D. The three brushes of the receiver B, just mentioned, are connected, by means of collector-rings a' b' c' and wires 51 52 53, with the respective coils 39 40 41, which serve to energize the respective poles a b c of receiver B. The brushes 48 49 50 of the receiver D are by means of the collector-rings d' e' f' and wires 54 55 56 connected with the respective coils 42 43 44, which are provided for the purpose 70 of energizing the respective poles d e f of the armature of the receiver D. By this arrangement the coils 39 40 41 42 43 44 are rendered to some extent independent of each other.

The two receiving instruments at the two stations are substantially alike, and this is also true of the transmitters. The transmitter A comprises a disk A¹ of insulating material, provided centrally with a pivot A², having a finger-piece A³. An insulating-sleeve A⁴ for the pivot A² is surrounded by a bearing A⁵, and upon this bearing is mounted an arm A⁶, provided with an insulating-sleeve A⁷ and free to turn upon the pivot A². An insulating-block A⁸ normally prevents electrical communication between the arm 6 and the sectors 8. (See Figs. 4 and 5.) A roller A⁹, of conducting material, is mounted upon the stem A¹⁰, connected to the block A⁸, and is revoluble, respectively, to other parts. When the arm 6 is moved circularly over the sectors, the roller A⁹ is brought into contact with each of the sectors successively. By this means each time the roller A⁹ passes over a sector, as indicated in Fig. 7, a metallic connection is momentarily formed between the sector and the arm 6 through the roller A⁹. Limiting-stops 57 58 are provided upon the transmitters for the purpose of preventing the arm from moving beyond predetermined points. (See Figs. 1 100

and 4.) The arms of the transmitters may be made to move clockwise, as indicated in Fig. 4 and the lower left-hand portion of Fig. 1, or counter-clockwise, as in the lower right-hand corner of Fig. 1, as desired. When the arm moves clockwise, the ordinals may be of the form shown in the left-hand portion of Fig. 1 and in Fig. 4, whereas if the arms move counter-clockwise the ordinals may have the form indicated in the lower right-hand portion of Fig. 1 and in Fig. 8. The direction of motion of the arm is therefore immaterial.

The receiver D is provided with two poles D' D², which are excited by the field 34, as above described. These poles are provided with convex faces D³, close to which the poles a b c of the armature are free to revolve. Rigidly connected with the armature is a gear-wheel D⁴, in mesh with the teeth on a dial-wheel D⁵. The dial-wheel is provided with a circle of ordinals D⁶, which are free to move relatively to a stationary pointer D⁷. The receiver B is similarly constructed; but, as above explained, the ordinals and the arm 7 may be arranged counter-clockwise, as indicated in the drawings, as desired.

The operation of my device is as follows: Supposing the operator at one of the stations desires to signal the operator at the other station and desires to learn whether the second-mentioned operator has received the signal and, if so, whether or not he has received it correctly, the signaling operator moves the arm 6 around, say, to the sector, which is shown in the drawings as provided with the ordinal "5." In doing this the arm 6 passes successively over the first five of the sector-shaped contacts, completing the circuit through the said contacts separately and individually. When the arm 6 moves from the dead sector 59 through the sector provided with the ordinal "1," the circuit is as follows: from the source of electricity 1, through wires 2 and 4, arm 6, sector numbered "1," wire 16, ring 10, wire 22, wire 28, brush 48, wire 54, coil 42, wire 38, brush 36, field-coil 34, wire 32, and wire 3, back to the source. When the arm 6 touches the contact provided with the ordinal "2," the circuit is as follows: source of electricity 1, wires 2 and 4, arm 6, sector numbered "2," ring 11, wires 23 and 29, brush 49, wire 55, armature-coil 43, wire 38, brush 36, field-coil 34, wires 32 and 3, back to the source. The two circuits just traced have the effect of separately energizing the armature-poles d and e of the receiver D, thus causing each of the poles mentioned to carry the armature one-third of a revolution. The contact 3 next being encountered completes the following circuit: The source of electricity 1, wires 2 and 4, arm 6, sector numbered "3," ring 12, wires 24 and 30, brush 50, wire 56, coil 44, wire 38, brush 36, field-coil 34, and wires 32 and 3, back to the source. The arm being carried farther, so that the roller encounters the sec-

tor numbered "4," the circuit is substantially the same as when it encountered the sector numbered "1," for the reason that sector numbered "4" has practically the same connections as sector numbered "1." The arm being moved still farther, so that the roller A⁹ encounters sector numbered "5," the circuit is again completed in substantially the same manner as when the roller encountered sector numbered "2." It will therefore be seen that when the arm 6 is moved over a given number of sectors the poles d e f, each rotating the armature one-third of a revolution, will cause an aggregate amount of rotation in the armature corresponding to the aggregate number of sectors brought successively into the circuit by means of the arm 6—that is to say, if the arm 6 be moved from one sector to another, the armature of the receiver D will move the dial-wheel D⁵ a corresponding distance, so that the stationary pointer D⁷ will indicate to the operator signaled that the signaling operator has moved his arm 6 to the first live sector. If the arm 6 be moved to any other sector—say to the one numbered "11"—the dial D⁵ will also rotate until it stops with its number "11" adjacent to the pointer. The operator who is signaled and who of course is in charge of the instruments C and B now turns his arm 7 to that sector corresponding to the one indicated by his dial. If his dial shows, say, the numeral "1" or "5" or "13," he turns his arm 7 to the sector numbered "1" or "5" or "13," as the case may be. The result is that the dial-wheel B⁵ upon the transmitter B rotates until the pointer stands adjacent to the numeral "1," "5," or "13," as the case may be, upon the dial. Of course these members are arbitrarily selected as examples for the purpose of illustrating the principle. It will be noticed that by tracing the circuits upon Fig. 1 the movements of the arm 7 do not affect the receiver D, but that they do affect the receiver B. The circuits may be traced from the source of supply 1 through the several armature-coils of the receiver B and will be found to correspond exactly with those already traced from transmitter A through receiver D. For instance, if arm 7 be moved upon the sector numbered "1" of the transmitter C, the circuit is as follows: from the source of electricity 1, through the wires 3 and 5, arm 7, sector numbered "1," wire 19, ring 13, wires 27 and 28, brush 45, wire 51, armature-coil 39, wire 37, brush 35, field-coil 33, wire 31, wire 2, back to the source. The other circuits may be traced successively, as above indicated, with reference to the use of transmitter A and receiver D. It will be noticed, therefore, that either operator can use his own transmitter to actuate the receiver of the other operator, but is unable to actuate his own receiver. It is the duty of either operator upon being signaled to answer the signal, so as to indicate to the signaling operator

that the signal is understood and also to indicate which particular ordinal is understood by the signal. In this way mistakes may be avoided and for the reason that if the signaling operator is not satisfied with the answer made from the operator signaled he will know that he has been misunderstood and will take immediate steps to prevent any mischief being accomplished thereby. This he can do by sending another signal or by any other preferred means. The arms 6 7 are immediately moved back to the starting-point after each signal. By this means the instruments are corrected, as it were, after each successive use—that is to say, if through accident the arm should pass over one of the sectors without completing the circuit or if some unauthorized person should tamper with one of the dials or with any part of the apparatus, so as to prevent exact correspondence between the respective receivers and transmitters at the different stations, the movements of the respective arms 6 7 back to the dead sectors 59 60 cause both transmitters and receivers to start from a common point or its equivalent. By this means any disparity that may occur between the receiver and a transmitter actuating it will be removed before the instruments are used again.

It will be noted that while the arm of the transmitter and the armature of the receiver each move with a step-by-step motion and while the dial moves synchronously with the arm, yet the number of revolutions of the armature have no relation to the number of movements of the arm. The arm in moving over six sectors does not make half of a complete revolution, yet during this movement the armature makes two complete revolutions.

Of course any number of sectors may be employed.

I do not limit myself to the apparatus described above or to any particular apparatus, as the mechanism for carrying out my invention may be varied considerably without departing from the scope of my invention. The above description is merely intended to show the application of my invention to one particular form of device.

If desired, a single set of instruments may be used, as indicated in Fig. 1^a. From the source of electric current 61 a wire 62 leads to the arm 63, which moves over sectors 64, substantially as described above. The sectors 55 are connected with the rings 65 66 67, and these rings are connected by wires 68 69 70 with brushes 71 72 73, resting upon collector-rings 74 75 76. The collector-rings are connected by wires 77 78 79 with coils 80 81 82 upon cores *r s t*. A return-wire 83 is connected with the collector-ring 84, and thereby with the brush 85, and this brush is connected by the wire 86 with the field-coil 87. From the field-coil the wire 88 leads back to the source of electrical supply. The circuit is

substantially the same as those already described and may be readily traced.

My invention may be used in various relations. It might be advantageously employed, for instance, in a structure such as the Brooklyn bridge, where it frequently happens that an officer located upon one part of the bridge desires to signal an engineer or other operative or officer located upon another part of the bridge. The invention might also be used to advantage in hotels and in connection with block-signals of railways. It is impossible, however, to enumerate the many diversified ways in which my invention may be used, and I therefore make no attempt to do so in this specification. The scope of my invention is pointed out in the following claims.

Having thus described my invention, I claim as new and desire to secure by Letters Patent—

1. An electric signal, comprising an electric motor provided with a revoluble armature having a plurality of separate poles, conducting-wires separately connected with said poles for energizing the same one at a time, a transmitter provided with a plurality of circularly-disposed contacts connected separately with said conducting-wires, manually-operated mechanism for energizing said contacts one at a time, and a source of electricity connected with said manually-operated mechanism and with said motor.

2. An electric signal, comprising an electric motor provided with a revoluble armature having a plurality of separate poles, conducting-wires separately connected with said poles for energizing the same one at a time, a transmitter provided with a plurality of circularly-disposed contacts connected separately with said conducting-wires, a manually-operated electrode free to move circularly over said contacts so as to engage the same one at a time in a predetermined order, a source of electrical supply connected with said revoluble armature, and means for periodically closing the circuit between said source of electrical supply and said revoluble electrode.

3. An electric signal, comprising a transmitter provided with contacts, a manually-operated contacting member disposed adjacent to said contacts and free to engage the same successively in a predetermined order, an electric motor provided with an armature having a plurality of poles, separate line connections from said contacts to said separate poles of said armature for the purpose of energizing the same synchronously with the successive engagement and disengagement of said contacts by said contacting member, a source of electricity connected with said contacts and with said armature, and mechanism actuated by said motor for indicating successive current-phases passing through said armature.

4. An electric signal, comprising an electric motor provided with a revoluble armature

having a plurality of separate poles, manually-operated mechanism connected separately with said poles for energizing the same independently of each other, thus giving a step-by-step movement to said armature, and means for indicating individually and collectively the several movements of said armature.

5. An electric signal, comprising an electric motor provided with a revoluble armature 10 having distinct poles spaced apart from each other, separate wires connected with said poles for actuating the same step by step, means controllable at will for energizing said wires one at a time, and mechanism actuated by said 15 motor for indicating the cumulative effect of several successive movements of said armature.

6. In an electric signal, the combination of a revoluble armature having a plurality of 20 poles spaced apart from each other, conducting-wires connected separately with said poles for energizing the same one at a time,

and manually-operated electric mechanism for energizing said wires successively.

7. In an electric signal, the combination of 25 a motor provided with a revoluble armature having a plurality of separate poles spaced apart from each other, conducting-wires connected separately with said poles for energizing the same one at a time, mechanism connected with said armature for indicating the 30 cumulative effect of several successive movements of said armature, separate contacts connected with said wires for energizing the same individually, and mechanism controllable 35 at will for successively closing said contacts.

In testimony whereof I have signed my name to this specification in the presence of two subscribing witnesses.

JOSEPH E. FELLER.
